UNITED STATES PATENT OFFICE.

JACOB STEPHANS, OF PAWTUCKET, RHODE ISLAND.

BOLT-POINTING MACHINE.

SPECIFICATION forming part of Letters Patent No. 691,198, dated January 14, 1902.

Application filed May 9, 1900. Serial No. 16,014. (No model.)

To all whom it may concern:

Be it known that I, JACOB STEPHANS, a citizen of the United States, residing at Pawtucket, in the county of Providence and State 5 of Rhode Island, have invented a new and useful Improvement in Bolt-Pointing Machines, of which the following is a specification.

The invention has reference to an improvement in machines for shaping the ends of screw-bolts; and it consists in the peculiar construction and combination of parts whereby two bolts may be simultaneously or successively operated upon, as will be more fully 15 set forth hereinafter.

The object of the invention is to increase the output and reduce the cost of attendance in the use of the machine.

Figure 1 is a side view of the bolt-pointing 20 machine. Fig. 2 is a front view of the same. Fig. 3 is a vertical sectional view taken on the line of one of the two spindles and the carriages. Fig. 4 is a vertical sectional view on a line through the center of the machine. 25 Fig. 5 is a front view of the fork-support, and Fig. 6 is a perspective view of the holder for the head of the bolt.

In the drawings, *a* indicates the standard, consisting of a box-like casting forming the 30 support of the parts of the machine and having the extended base *a'*. From the standard *a* extend in the front of the machine the beds *a²* *a²*, strengthened by the brackets *a³* *a³*. A trough *a⁴* extends on the two sides and across 35 the front and is preferably cast in one piece with the base and the beds *a²* *a²*. The said trough *a⁴* serves to support a supply of bolt-blanks within the easy reach of the operator. The bases *a⁵* *a⁵* are supported on the beds *a²*. 40 Each base is provided at opposite sides with the grooved ways *a⁶*, in which the carriages *b* slide. On each of the carriages *b* a standard *b'* is secured, in which the longitudinally-adjustable spindle *b²* is supported. The head 45 *b³* of the spindle *b²* is provided with a recess, in which the stud *b⁴* of the work-holder *b⁵* is secured by a set-screw, as shown in Fig. 3. The work-holder is formed to support the work and hold it against rotation.

50 In the drawings the work-holder is shown adapted to support the hexagonal head of a screw-bolt blank and hold the same against

rotation. For other forms of heads or work especially-constructed work-holders are used.

The standard *a* preferably extends upward 55 to form the two transversely-extending pillow-blocks *a⁷* *a⁷* in one casting, and in these pillow-blocks *a⁷* *a⁷* the bearings for the two spindles *c* *c* are placed and secured by the caps *a⁸* *a⁸*. The brackets *a⁹* extend from the front 60 pillow-block below each spindle and form the support of the adjustable fork-support *a¹⁰* for the bolt. The sleeve *a¹¹* is secured to the standard and forms the journal-bearing for the central driving-shaft *d*. The two brackets 65 *a¹²* *a¹²* extend from the pillow-blocks *a⁷* *a⁷* upward to form the bearing for the idle pulley *c²*.

The machine is driven by means of a belt from some prime motor, as is indicated in Fig. 2. The belt (indicated in broken lines) 70 extends around the pulley *c'*, secured to the right-hand spindle *c*, thence over the idle pulley *c²*, and from this around the pulley *c³*, secured to the left-hand spindle *c*. By widening the machine, so as to take in three or 75 more carriages *b* and spindles *c*, the addition of one or more idle pulleys will permit the belt to simultaneously operate three or more spindles. Each of the spindles *c* is provided at the front end with a shaper *b⁶* of such 80 form as will cut and finish the end of the bolt into the desired form. In Fig. 3 a shaper is shown for forming a semispherical end on the bolt. The shaper *b⁶* is secured in the head *b⁷*, in which also a perforated center-block *b⁸* 85 is secured, by which the bolt is held centrally and supported near the shaper, as shown in Fig. 3.

To the rear end of one of the spindles *c* the pulley *c⁴* is secured, and this pulley is connected by means of a belt with the pulley *c⁵*, secured to a shaft journaled in bearings formed in the standard *a*, on the inner end of which shaft the pinion *c⁶* is secured and engages with the gear *c⁷*, secured to the central shaft *d*. The shaft *d* has suitable bearings in the standard *a* and a bearing in the conical sleeve *a¹¹*. Through the shaft *d* motion is transmitted to a transversely-extended shaft, by which the carriages *b* are operated. This transmission of motion to the carriages *b*, by which the bolts are fed to the shapers, may be continuous; but in the preferred form I provide the shaft *d* with the clutch *d'*, loose

on the shaft, and the sliding clutch part d^2 , connected by a groove and feather with the shaft, and connect the hand-lever d^3 , which is pivoted at its lower end in the usual manner, with the sliding part d^2 of the clutch, so that the power-transmitting part of the mechanism operating the carriages may be connected or disconnected at will by the operator.

10 The bevel-gear d^4 on the clutch part d^1 engages with the bevel-gear d^5 on the transverse shaft d^6 . Below each sliding carriage b a cam d^7 is secured to the shaft d^6 . In a machine having two sets of spindles $c c$ and 15 two carriages $b b$, as shown in the drawings, I prefer to set the cams d^7 at right angles to each other. When three or more spindles and carriages are used in one machine, the cams may be set so as to feed the bolts successively 20 or in pairs. The cam d^7 acts on the roller d^8 , journaled in a bracket on the carriage b , to move the bolt f to the shaper, and when the highest point of the cam d^7 has passed the roller d^8 the weight d^9 , secured to one end of 25 the strap d^{10} , the other end of which is secured to the sliding carriage b , said strap d^{10} extending over the pulleys d^{11} and d^{12} , draws the carriage b backward, when the pointed bolt is removed and a new bolt-blank inserted to 30 be turned at the next forward movement of the carriage.

In machines of this construction one attendant may conveniently supply the blank for a two or even a four spindle machine. 35 The labor charge can thereby be reduced to one-half or one-fourth, while the cost of a two or four spindle machine, producing two or four times the number of bolts, is not proportionally increased.

40 Having thus described my invention, I claim as new and desire to secure by Letters Patent—

1. In a bolt-pointing machine, a standard having a plurality of shaper-carrying spindles arranged thereon and longitudinally thereof, a shelf or table secured to one side of the standard and longitudinally thereof, a plurality of work-feeding devices arranged on the table, a pulley on each spindle-shaft, 45 a single belt running on all the pulleys to rotate them, a single shaft arranged longitudinally of the shelf and operating the work-feeding devices, and operating mechanism connecting the shaft and one of the spindles, 50 substantially as described.

2. In a bolt-pointing machine, a standard having a shelf or table arranged at one side and longitudinally thereof, a series of work-feeding devices arranged upon and longitudinally of the shelf, a shaft arranged longitudinally of the shelf and provided with a series of cams, said cams adapted to operate the work-feeding devices, a second and driving shaft mounted on the standard at right 65 angles to the cam-shaft, and means including

a clutch for connecting the driving-shaft with the cam-shaft, substantially as described.

3. The combination of a rotary tool-carrier and a work-holder, the two said parts having relative adjustment toward and away from each other, the said tool-holder being adapted to receive the piece of work laterally so that it may be lowered therein into position for the tool to act upon it, and an independent support located between said parts for supporting the work from beneath, substantially as and for the purpose set forth.

4. In a bolt-pointing machine, a hollow, cast-metal standard having two pillow-blocks forming the support of two or more spindles, 80 forwardly-projecting beds forming the supports for the blank-feeding devices, a trough extending along the two sides and the front of the forwardly-projecting beds, ways on the beds parallel to the spindles, reciprocating carriages on the ways, adjustable blank-supports on the carriages, means for rotating the spindles, a shaft extending longitudinally parallel with the spindles, mechanism connecting one of the spindles with the longitudinal shaft, a transversely-extending shaft, and cams on the transverse shaft for actuating the carriages, whereby the blanks are automatically fed to the cutter and withdrawn, as described.

5. In a bolt-pointing machine, in combination with two or more spindles, mechanism for rotating the spindles, and two or more work-supporting carriages sliding in ways parallel to the axis of the spindles, of a shaft supported in bearings parallel to the axis of the spindles, a clutch on the shaft, an operating-lever connected with the sliding part of the clutch, a bevel-gear on the clutch, a transverse shaft provided with a bevel-gear 105 engaging with the bevel-gear on the clutch, cams on the transverse shaft for moving the carriages toward the spindles, and weights connected with straps to the carriages for moving the carriages back from the spindles, 110 as described.

6. In a bolt-pointing machine, the combination with the spindles $c c$, placed side by side, the cutter-heads b^7 on the spindles, the shaper b^6 , and the perforated block b^8 in the head of the carriages $b b$, the standard b^9 on the carriages, the spindle b^2 , the head b^3 on the spindle, the holder b^5 open on one side formed to receive the head of the bolt and hold it against rotation, a stud on the holder detachably secured in the head b^8 , mechanism for rotating the spindles, and mechanism for reciprocating the carriages, as described.

In testimony whereof I have signed my name to this specification in the presence of 125 two subscribing witnesses.

JACOB STEPHANS.
